UNITED STATES PATENT OFFICE.

JOHN G. BROMAN, OF CHICAGO, ILLINOIS.

LOCOMOTIVE-BOILER.

1,263,844.

Specification of Letters Patent. Patented Apr. 23, 1918.

Application filed April 24, 1916. Serial No. 93,149.

To all whom it may concern:

Be it known that I, JOHN G. BROMAN, a citizen of the United States, and a resident of the city of Chicago, in the county of Cook and State of Illinois, have invented certain new and useful Improvements in Locomotive-Boilers; and I do hereby declare that the following is a full, clear, and exact description of the same, reference being had 10 to the accompanying drawings, and to the numerals of reference marked thereon, which form a part of this specification.

This invention relates to an improved type of locomotive boiler wherein means are provided to insure circulation of the water, thereby utilizing to the fullest extent the heating effect of the boiler, and with other means acting further, due to the course of movement of the water, to skim the surface 20 of impurities and also to prevent entrained water passing with the steam evolved into the steam dome of the boiler.

It is an object therefore of this invention to construct a locomotive boiler wherein 25 means are provided therein to automatically induce a circulation of water within the boiler by utilization of a thermo-siphon effect, and with means acting further, due to the course of movement of the water, to prevent entrance of entrained water with the steam into the steam dome of the boiler.

It is also an object of this invention to construct a locomotive boiler provided with baffle means mounted therein operating to 35 cause the water in the boiler to move according to a predetermined course of movement due to a thermo-siphon effect as the water is heated, and with means utilizing the course of movement of the water to free the 40 steam evolved therefrom from entrained moisture as it enters the steam dome of the boiler.

It is furthermore an important object of this invention to construct a locomotive 45 boiler of substantially standard design, but equipped on its interior with baffling means so disposed as to cause a thermo-siphon effect of the heated water to set up a predetermined course of movement thereof to obtain the greatest amount of heat from the 50 tubes due to the circulation of the water, and utilizing the movement of the water in freeing the steam evolved from entrained moisture as it passes into the steam dome.

It is finally an object of this invention to provide an improved construction of loco-

motive boiler wherein a circulation of water within the boiler is insured, and as well, separation of the moisture from the steam entering the steam dome, and with a skimming device to utilize the circulation of the water to skim impurities from the surface thereof for withdrawal from the boiler from time to time.

The invention (in a preferred form) is 65 illustrated in the drawings and hereinafter more fully described.

In the drawings:

Figure 1 is a longitudinal central section taken through a locomotive boiler, with 70 parts omitted and parts shown in elevation, illustrating the same constructed and arranged according to the principles of my invention.

Fig. 2 is a detail section taken on line 75 2-2 of Fig. 1.

Fig. 3 is a detail section taken on line 3-3 of Fig. 1.

Fig. 4 is a view similar to Fig. 1, of another type of boiler constructed to utilize 80 the principles of my invention.

Fig. 5 is a detail section taken on line 5-5 of Fig. 4.

Fig. 6 is a detail section taken on line 6-6 of Fig. 4.

As shown in the drawings:

In the construction shown in Figs. 1, 2 and 3, the barrel or shell of the boiler, shown as a horizontal locomotive type, is denoted as a whole by the reference numeral 1, and 90 extending longitudinally therethrough are fire tubes 2, connected at their forward ends into a front tube sheet 3, and at their rear ends in a back tube sheet 4, the front tube sheet 3, separating the water compartment 95 in the boiler from the smoke box, denoted by the reference numeral 5, and the back tube sheet 4 forming the front wall of a fire box 6. Mounted on the top of the shell 1, over a large opening provided therein is a 100 steam dome 7, and secured on the inner surface of the shell 1, at one side of said steam dome and curving downwardly therebeneath is a baffle plate 8. Secured upon the rear surface of the front tube sheet 3, and projecting rearwardly within the boiler and curving slightly upwardly is another baffle or skimming plate 9, capable of serving two purposes, that is, to deflect the circulating water downwardly and to skim impurities 105 from the surface thereof.

Mounter transversely within the shell 1,

at the lower portion thereof and extending longitudinally and inclining upwardly from the front toward the rear end of the boiler is a long baffle plate 10, and preferably 5 one row of tubes 2, usually provided in the boiler, is omitted, to permit the attachment of said baffle plate 10, in place. As clearly 10 shown in Fig. 1, the forward end of said long inclined baffle plate 10, terminates a short distance back of the rear end of the baffle or skimming plate 9, and the rear end of said long baffle plate 10, extends to within a short distance of the tube sheet 4, of the fire box. Due to the concavity of the top 15 surface of the skimming plate 9, the impurities skimmed from the surface of the water will be collected on said plate 9, and may be blown off from time to time through a valve blow off pipe provided for the purpose.

In the construction illustrated in Figs. 4, 5, and 6, I have shown a slightly different type of boiler wherein the shell is denoted as a whole by the reference numeral 11, and is 20 provided near its forward end with a front tube sheet 12, and mounted within the shell and spaced from the walls thereof at the rear end of the boiler, is a fire box 13, having a front wall affording a back tube sheet 14, 25 and side walls 15, which extend downwardly spaced from the shell of the boiler, as shown in Fig. 5. A plurality of fire tubes 16, extend between the front tube sheet 12, and rear tube sheet 14, affording communication 30 between the fire box 13, and the smoke box at the forward end of the boiler. Slightly below the middle portion of said boiler one row of tubes is omitted, and mounted transversely within the boiler and 35 inclining upwardly and extending rearwardly therein is a long baffle plate 17, the forward end of which is spaced from the front tube sheet 12, and the rear end of which extends closely adjacent the tube sheet 14. Mounted in the water leg on each 40 side of the fire box 13, between the walls 15, of the fire box and the shell 11, of the boiler is a curved plate 18, the lower end of which is substantially in alignment with the rear 45 end of the inclined baffle plate 17, and the upper end of which is secured substantially flush with the upper end of the fire box 13. As in the previous construction described, a steam dome 19, is mounted over a relatively 50 large aperture in the top of the shell 11, and secured at one side thereof and projecting forwardly and curving downwardly beneath said steam dome, is a baffle plate 20.

The operation is as follows:

60 Referring first to the construction illustrated in Figs. 1 to 3 inclusive, the hottest portion of the heating means within the shell 1, is at the rear end of the boiler around the fire box 6, and rear end of the fire tubes 2, so that consequently there is a tendency

for the water in the boiler to rise at the rear end thereof and flow downwardly in a circulating movement at the forward end thereof. Without baffling means, however, such as I have provided, the swaying and jolting 70 movements of the locomotive and rapid ebullition of steam would prevent any well defined circulation of water taking place. However, by interposing the relatively long inclined baffle plate 10, in place, and the 75 skimming baffle plate 9, a guiding means is provided which serves to aid the water in taking up a natural circulating movement due to the thermo-siphon effect caused by the difference in temperature of the heating 80 elements at the opposite ends of the boiler. As a consequence of such circulating movement taking place, the major portion of the steam evolved will occur at the rear end of the boiler, and will tend to move along with 85 the circulating water toward the forward end of the shell, and will be deflected downwardly by the baffle plate 8, beneath the dome 7, so that water entrained with the steam will be thrown out and the steam will 90 rise upwardly around the edge of the baffle plate 8, into the steam dome 7, in a comparatively dry condition. As the surface water within the boiler flows farther toward the baffle or skimmer plate 9, impurities on 95 the surface thereof are skimmed off and will settle within said curved baffle plate 9, as the water circulates downwardly deflected thereby in a natural thermo-siphon movement.

In the form of device illustrated in Figs. 4, 5, and 6, the general operation is substantially the same, that is, the thermo-siphon effect is aided by the interposition of a long inclined baffle plate 17, and curved baffle 105 plates 18, in the water legs of the boiler on each side of the fire box 13. As in the construction previously described, a greater amount of steam will be evolved at the rear portion of the boiler substantially above the 110 fire box 13, and will move therewith in the general direction of circulation of the water being deflected downwardly by the baffle plate 20, and thereby freed of entrained moisture to rise in a relatively dry condition 115 into the steam dome 19.

I am aware that the details of construction may be varied through a wide range without departing from the principles of this invention, and I therefore do not pur- 120 pose limiting the patent granted otherwise than necessitated by the prior art.

I claim as my invention:

In a device of the class described, the combination with a boiler, tubes and front 125 and rear tube plates, of a skimmer and baffle plate secured to the front tube plate adjacent the top of the water line and curved upwardly presenting a curved lower surface, and a baffle plate secured adjacent the bottom of 130

the boiler inclining downwardly toward the front of the boiler and extending from adjacent the rear tube plate forwardly to have its forward edge lie in approximately vertical alinement with the rear edge of the upper baffle and skimmer plate.

5 In testimony whereof I have hereunto sub-

scribed my name in the presence of two subscribing witnesses.

JOHN G. BROMAN.
